WHEEL MOUNTING LUG

Leon A. Theissen, St. Peter, and Bernard E. Hogan, Jr.,
North Mankato, Minn., assignors to Miller Motors, Inc.,
Mankato, Minn., a corporation of Minnesota

Filed June 7, 1967, Ser. No. 7,386

Term of patent 14 years

(Cl. D54—1)

FIGURE 1 is a front elevational view of a wheel mounting lug embodying our design;

FIGURE 2 is a right end elevational view of the same, the left end elevation view being a mirror image of the same;

FIGURE 3 is a rear elevational view of the same;

FIGURE 4 is a top view of the same, and

FIGURE 5 is a bottom view of the same.

We claim:

The ornamental design for a wheel mounting lug, as shown and described.
